UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 15, 1919, Serial No. 317,830. Renewed February 27, 1922. Serial No. 539,765.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus of the type in which traffic governing means located on a railway car or train is controlled by energy received from the track rails.

15 One feature of my invention is the provision of a system of this character which is adapted for use in connection with direct current track circuits of the usual type.

I will describe several forms of system 20 embodying my invention, and will then point out the novel features thereof in claims.

In the accompanying drawings, Fig. 1 is a diagrammatic view showing one form and arrangement of track-way apparatus 25 embodying my invention and adapted particularly for use on a track over which traffic normally moves in one direction only. Fig. 2 is a diagrammatic view showing one form of vehicle carried apparatus embodying my invention and adapted for cooperation 30 with the trackway apparatus shown in Fig. 1. Fig. 3 is a view showing a modification of the vehicle carried apparatus shown in Fig. 2 and also embodying my invention. Figs. 4, 4^a and 4^b are diagrammatic views which when placed end to end in the order named, show one form of trackway apparatus adapted for use on single track railways over which traffic moves in both directions, and also embodying my invention.

Similar reference characters refer to similar parts in each of the several views.

Referring first to Fig. 1, the reference characters 1 and 1^a designate the track rails 45 of a railway over which traffic normally moves in the direction indicated by the arrow. These rails are divided by insulated joints 7 into a plurality of blocks, of which only two complete blocks A—B and B—C 50 are shown in the drawing.

Each block is provided with a track circuit comprising as usual the track rails of

the block, a source of current connected across the rails at the exit end of the block, and a track relay connected across the rails 55 at the entrance end of the block. As here shown, the source of current for each track circuit is a battery designated by the reference character D with an exponent corresponding to the particular location, this battery being reversibly connected with the rails by a pole-changer designated P with a suitable exponent. The track relay for each block is designated H with an exponent corresponding to the location, each of these 60 relays, of course, being adapted for operation by direct current. Each track relay is of a polarized type, comprising two neutral armature contacts 2 and 8 and a polarized armature contact 4. It follows, of course, 65 that the polarized contact 4 will be swung in one direction or the other according as the pole-changer for the corresponding track circuit is in one position or the other, and that the neutral contacts 2 and 8 of each 70 relay will be closed or opened according as the relay is energized or deenergized.

Located adjacent the entrance end of each block is a roadside signal designated by the reference character S with an exponent corresponding to the location. Each of these signals, as here shown, is of the semaphore type adapted to indicate "stop", "caution" or "proceed", according as the semaphore is in the horizontal, the inclined or the vertical 75 position. Each signal is controlled by the track relay for the corresponding block through the medium of a caution indication circuit and a proceed indication circuit. Considering signal S^B, for example, the caution indication circuit is from one terminal B of a suitable source of current such as a battery, through the neutral contact 2 of relay H^B, wire 3, and the operating mechanism 80 of signal S^B to the other terminal O of the same source of current. The proceed indication circuit for this signal (shown open in the drawing) is from battery terminal B, through contact 2, polarized contact 4, wire 5, and the operating mechanism of signal 85 S^B, to the other battery terminal O. This proceed indication circuit is closed only when polarized contact 4 is swung to the left, and this occurs only when the relay H^B 90

is supplied with current of what I will term "normal" polarity. When the relay is supplied with current of the opposite or "reverse" polarity, contact 4 is open as shown, 5 so that the signal indicates caution.

The pole-changer P, which is included in each track circuit, is operated by the signal S for the block next in advance, and in such manner that the polarity of the current supplied to the track circuit is normal when 10 the signal indicates proceed or caution, and reverse, when the signal indicates stop.

The operation of the apparatus thus far described is in accordance with usual and 15 standard practice, and hence it is so well understood that no explanation is necessary.

For each block I have provided means for connecting a source of alternating vehicle governing current across the rails at the 20 exit end of the block in series with the track battery for the block. As here shown, this means comprises a transformer designated by the reference character T with an exponent corresponding to the location, the 25 secondary of which is included in the connection between the lower track rail 1 and the track battery D. The primary of each transformer T is at times connected with a transmission line E, which is supplied 30 with alternating vehicle governing current by a suitable generator F. The primary circuit of each transformer T includes the neutral contact 8 of the track relay for the block next in advance, so that vehicle governing current is supplied to the rails of 35 each block when the track relay for the block next in advance is energized, but not when such track relay is deenergized. In other words, this current is supplied to each 40 block only when the block next in advance is unoccupied.

In accordance with usual practice, a non-inductive resistance 6 is interposed in the connection between the track rail 1 and the 45 secondary of transformer T to limit the current drawn from this transformer and from the battery D when a car or train is near the exit end of the block.

Referring now to Fig. 2, the vehicle carried apparatus in the form shown herein includes two laminated soft iron cores 9 and 9^a, mounted on the vehicle in advance of the forward axle and located over the two track rails 1 and 1^a respectively. Each of these 55 cores is U-shaped, with its legs pointing downwardly, and each core is disposed transversely with respect to the rail. The two cores 9 and 9^a are provided with windings 10 and 10^a, respectively. It is apparent, therefore, that when alternating current flows in either rail, part of the magnetic lines of force surrounding such rail will 60 pass through the core which is directly over the rail, and so will induce an alternating 65 potential in the coil carried by such core.

The two coils 10 and 10^a are included in series in a circuit a, which circuit also includes a condenser 16. The two coils are so connected in this circuit that the potentials induced in these coils by an alternating current flowing in opposite directions in the two rails are additive, so that the vehicle governing current in the track rails will cause an alternating current to flow in circuit a. The coils 10 and 10^a 75 are so wound as to have high inductance while the condenser 16 has a comparatively small capacity, and these parts are so adjusted that circuit a is tuned to resonance at the frequency of the vehicle governing current; it follows, therefore, that condenser 16 will be charged to a comparatively high potential by the comparatively feeble current induced in circuit a by the vehicle governing current in the track rails. This 80 potential, is however, too feeble to reliably actuate traffic controlling apparatus of a rugged character, hence I have provided suitable amplifying apparatus, which, in the form here shown, comprises three electron tubes K', K^a and K^b. Each of these tubes (see tube K') comprises a vacuum bulb 11 containing a filament 12, a plate 14, and a grid 13 interposed between the filament and the plate. 90

The filament 12 of the electron tube K' is constantly heated by a battery 15, the circuit being from the upper terminal of this battery, through wire 19, adjustable resistance 17, filament 12, wire 48, adjustable resistance 18, and wire 30 to the lower terminal of battery 15. The battery 15 may be a car lighting battery or a headlight generator, the potential of which is preferably about 32 volts. 100

The electron tube amplifier K' is provided with a grid circuit which passes from coil 10 through wires 20^a and 20, grid and filament of tube K', wire 48, resistance 18, and wires 30 and 21 to coil 10^a and coil 10. 110 By virtue of the adjustable resistances 17 and 18 in the filament and grid circuits of amplifier K', these circuits may be so adjusted that the potential of the grid 13 is always negative with respect to that of the negative end of filament 12, so that there will be no transfer of electrons between the grid and filament. The difference of potential between these two parts is preferably 1.5 115 volts. 120

An alternating potential impressed upon the grid and filament, due to circuit a, in excess of 1.5 volts will therefore permit the grid to become positive and permit a flow of electrons from the filament to the grid, thereby robbing the oscillating circuit of energy and hence limiting the value of the oscillating voltage to approximately 1.5 125 volts irrespective of the value of the track current, as long as the latter value is above 130

- the minimum which will induce 1.5 volts. Therefore the system will operate reliably and uniformly over a wide range of track currents above a predetermined minimum.
- 5 The amplifier K' is provided with a plate circuit which includes a separate battery 22 in series with battery 15, the total potential being preferably about 50 volts. The plate circuit of K' is from the upper or positive 10 terminal of battery 22, through wire 23, primary winding of a step-up transformer J', plate and filament of amplifier K', wire 48 resistance 18, wire 30, battery 15, wire 25 to battery 22. Connected in multiple with 15 the primary of transformer J' is a condenser 24, the local circuit which comprises this condenser and primary winding being tuned to resonance at the frequency of the vehicle governing current. It will be seen from 20 70 the foregoing that the minute variations of potential in the receiving circuit a will create variations of considerably greater magnitude in the strength of the current from battery 22 in the plate circuit of amplifier K'.
- The filaments of amplifiers K² and K³ are connected in series and are supplied with current from battery 15, the circuit being from the upper terminal of this battery, 30 through wires 19 and 26, filament and amplifier K², wire 27, filament of amplifier K³, wire 28, adjustable resistance 29, and wire 30 to battery 15.
- Amplifier K² is provided with a grid circuit which passes from the upper terminal of the secondary of transformer J', through wire 31, grid and filament of amplifier K², wire 27, filament of amplifier K³, wire 28, adjustable resistance 29 and wire 32 to the 40 lower terminal of the secondary of transformer J'. The point of connection of wire 32 to resistance 29 is so chosen that the grid of K² will be sufficiently negative with respect to the negative end of the filament of K² that there will be no transfer of electrons between the grid and filament. That is, this negative potential should equal or exceed the maximum potential of the secondary of transformer J'. Under these circumstances 45 the latter will operate under practically "open circuit" conditions and hence may have a high number of secondary turns, giving a very high voltage amplification.
- The plate circuit of amplifier K² is supplied with direct current by the generator G of a motor generator set Z, the motor M of which is constantly supplied with current by the battery 15. The current delivered by generator G is preferably about 350 volts.
- 50 The plate circuit for amplifier K² is from the upper terminal of generator G, through wires 33 and 34, primary of a transformer J², plate and filament of amplifier K², wire 27, filament of amplifier K³, wire 28, resistance 29, and wire 30 to the lower terminal 55 of generator G. A condenser 24^a is connected in multiple with the primary of transformer J², the local circuit comprising this primary and condenser being tuned to resonance at the frequency of the vehicle governing current. The ratio of transformer J² is preferably about one to two. 70
- It follows then, that variations in the plate current of amplifier K' will be reproduced as an alternating difference of potential in the 75 grid circuit of amplifier K², resulting in similar variations of much greater amplitude in the current in the plate circuit of amplifier K².
- Amplifier K³ is provided with a grid circuit which passes from the upper terminal of the secondary of transformer J², through wire 35, grid and filament of amplifier K³, and wire 36 to the lower terminal of the secondary of transformer J². The grid of 80 85 amplifier K³ is thus at the same potential as the negative end of the filament of K³, thus permitting a greater flow of current from the plate to the filament with a given plate to filament potential, and hence permitting a greater output, than would be the case if the grid were made negative. It follows then that the variations in the plate current of amplifier K² are reproduced as an alternating difference of potential in the 90 95 grid circuit of amplifier K³.
- The plate circuit of amplifier K³ includes the two stator windings 38 and 38^a of an induction motor relay L, winding 38 being shunted by a condenser 39 to provide the 100 proper phase displacement between the currents in these two windings. This plate circuit passes from the upper terminal of generator G, through wires 33 and 37, winding 38 and condenser 39 in multiple, winding 105 38^a, wire 40, plate and filament of amplifier K³, wire 28, resistance 29, and wire 30 to the lower terminal of generator G. With the apparatus proportioned substantially as set forth, the pulsations of the current thus supplied to the stator windings of the relay L will be of sufficient amplitude to actuate the rotor 41 of this relay reliably even though the relay be of a rugged commercial type. This relay may be constructed to operate 110 115 on a normal energy of 3 watts.
- The plate circuit of amplifier K' is preferably energized from the battery 22 instead of from generator G, to avoid the possibility of the generator of alternating current in 120 this circuit from any source other than the track rails, since such current, even if of minute amplitude, would be amplified by tube K' and K², and might thus result in false operation of the system. 125
- As here shown, the relay L controls a brake application magnet N and a cab signal S^o. The magnet N controls the vehicle brakes in such manner that the brakes are applied when this magnet is de-energized. 130

The circuit for magnet N is from battery 15, through wire 19, contact 42 of relay L, wire 44, winding of magnet N, and wires 45 and 30 to battery 15. The contact 42 is closed when relay L is energized, and, consequently, it will be seen that the magnet is energized whenever relay L is energized, that is, whenever the vehicle is supplied with vehicle governing current from the track rails. The cab signal S^D comprises a green lamp and a red lamp, which lamps indicate "proceed" and "stop", respectively, when illuminated. These lamps are controlled by a contact 43 of relay L in such manner that the green or proceed lamp is illuminated when relay L is energized, and the red or stop lamp is illuminated when the relay is de-energized. The circuit for the green lamp is from battery 15, through wire 19, upper point of contact 43, wire 46, the green lamp, and wire 30 to battery 15. The circuit for the red lamp is the same, except that it includes the lower point of contact 43 and wire 47.

The operation of the entire apparatus as thus far described is as follows:

Referring again to Fig. 1, it will be seen that the block to the left of location A is occupied by a vehicle V, which vehicle I will assume is equipped with the governing apparatus shown in Fig. 2. Inasmuch as track relay H^A is energized, vehicle governing current is supplied to the rails of the block to the left of location A, so that relay L on vehicle V is energized, with the result that the brake controlling magnet N is energized and the green or proceed lamp is illuminated. As the vehicle V enters block A-B no change will occur in the vehicle carried apparatus, because this block is supplied with vehicle governing current due to the fact that relay H^B is energized. Block B-C is not supplied with vehicle governing current, however, because contact 8 of track relay H^C is open, due to the fact that the block to the right of location C is occupied by a vehicle V'. As the vehicle V enters block B-C, therefore, relay L will become de-energized, thereby extinguishing the green lamp, illuminating the red lamp, and de-energizing the brake controlling magnet N. The vehicle will, therefore, be brought to a stop or to a predetermined low speed, depending on the character of the apparatus interposed between magnet N and the braking system of the vehicle. If, while vehicle V is in block B-C, vehicle V' passes out of the block to the right of location C, vehicle governing current will immediately be supplied to the rails of block B-C, so that relay L on vehicle V will immediately become energized, and this vehicle may then resume full speed.

Referring now to Fig. 3, the apparatus shown in this view is similar to that shown in Fig. 2, the chief difference being that in

Fig. 3 the train controlling relay, which is here designated L', is of the direct current type, and the output of the amplifiers is transformed into direct current by a rectifying device U, which device in turn supplies energy to the relay L'. Another difference between the two views is that only two amplifiers K' and K² are employed in the apparatus shown in Fig. 3.

The filaments of the amplifiers K' and K² are constantly heated by current from battery 15, the circuit being from the upper terminal of this battery, through wires 19 and 139, filament of amplifier K², wire 140, adjustable resistance 29, wire 141, filament 80 of amplifier K', and wires 142 and 30 to battery 15. The grid circuit for amplifier K' is from coil 10^a through wire 143, battery 144, wire 145, grid and filament of amplifier K', wires 142 and 146 and coil 10 to coil 10^a. The function of the battery 144 is to maintain the potential of the grid 13 negative with respect to the filament 12. The plate circuit of amplifier K' is from battery 22, through wire 23, primary of transformer 90 J' and condenser 24 in multiple, wire 23^a, plate and filament of amplifier K', wires 142 and 30, battery 15, and wire 25 to battery 22. The secondary of transformer J' supplies an alternating difference of potential to the grid circuit of amplifier K², this circuit being from secondary of transformer J', through wire 31, grid and filament of amplifier K², wire 140, a portion of the adjustable resistance 29, and wire 32 to transformer J'. The plate circuit for amplifier K² is from generator G of the motor generator set Z, through wires 33 and 33^a, primary 147 of transformer J³, and condenser 154 in multiple wire 148, plate and filament of amplifier 105 K², wire 140, resistance 29, wire 141, filament of K', wire 142 to generator G. The local circuit including condenser 154 and the primary of transformer J³ is tuned to resonance at the frequency of the vehicle 110 governing current. The armature circuit of generator G is preferably shunted by a condenser 149, as shown, in order to damp out the commutator pulsations in the generator current. The rectifying device U 115 comprises a transformer J³ and two electron tubes K⁴ and K⁵, each of which is similar to the amplifiers K' and K² hereinbefore explained, and the filaments of which are constantly heated by virtue of a circuit 120 which passes from the upper terminal of battery 15, through wires 19 and 150, resistance 29^a, wire 151, filament of tube K⁵, wire 152, filament of tube K⁴, and wires 153 and 30 to battery 15. Transformer J³ is provided with two secondaries 147^a and 147^b, in series, whose outer terminals are connected to the plates of electron tubes K⁴ and K⁵ by wires 155 and 156 respectively, and whose inner terminals are connected together and to the 125 130

winding of relay L' by a wire 157. The circuit of secondary winding 147^a is from its right hand terminal to wire 157, winding of L' , wire 158, filament of K^4 to plate, and 5 wire 155 to winding 147^a. Since the electron tube possesses unidirectional conductivity, this circuit will in effect be open when the alternating potential across the transformer secondary is in such direction that the left 10 hand terminal is negative, and will permit current to flow through the relay only when the left hand terminal is positive. The circuit of secondary winding 147^b is from its left hand terminal to wire 157, winding of 15 L' , wire 158, filament of K^4 , filament of K^5 to plate, and wire 156 to winding 147^b. This circuit will evidently be effectively open when the right hand terminal is negative, and will permit current to flow through the 20 relay only when the right hand terminal is positive. Windings 147^a and 147^b therefore supply current to the circuit of L' during alternate half cycles, and the current through the winding of L' is unidirectional.

25 In order to lower the effective internal impedance of the electron tubes and hence to increase the current through L' , I connect the grid of K^4 by wire 159 to a point on resistance 29^a which is positive with respect to 30 the filament of K^4 and likewise connect the grid of K^5 by a wire 160 to a point positive with respect to the filament of K^5 .

It is understood that relay L' may control 35 suitable vehicle governing apparatus, such, for example, as the apparatus shown in Fig. 2, and controlled by relay L in that view.

Referring now to Figs. 4, 4^a and 4^b, I have here shown one form of trackway apparatus embodying my invention adapted 40 for use in connection with a single track signaling system of the type known as "absolute permissive block signaling". In this drawing, the reference characters 50, 50^a designate the track rails of a stretch of single track over which traffic moves in both 45 directions, and which stretch includes two passing sidings 51 and 52. The rails are divided by insulated joints 49 to form a plurality of sections 53-54, 54-55, etc., and 50 each section except the ones at which the passing sidings are located is further divided by similar insulated joints to form a plurality of sub-sections such as 54-54^a and 54-55. Each sub-section is provided with a 55 track circuit comprising a track battery D and a track relay designated by the reference character H with a suitable exponent, and each passing siding section 53-54 and 57-58 is provided with a similar track circuit.

60 Traffic along the stretch from west to east is governed by a plurality of roadside signals S^2 , S^4 , S^6 etc., while traffic along the stretch from east to west is governed by a plurality of signals S' , S^3 , S^5 etc. As here 65 shown, each signal is located adjacent the

junction of two track sections, although this exact location is not essential. Each signal is of the three-position semaphore type, arranged to indicate "stop", "caution" and "proceed", according as the semaphore 70 is in the horizontal, inclined or vertical position.

Each signal S is controlled by a line relay which is designated by the reference character R with the same exponent as that 75 of the signal which it controls.

Each signal is provided with a caution circuit and a proceed circuit. Referring particularly to signal S^5 , the caution circuit is from one terminal B of a suitable source 80 of current, through front point of contact 59 of relay R^6 , wire 60, operating mechanism of signal S^5 , wire 61, and contact 62 of relay R^6 to the other terminal O of the same source 85 of current. The proceed circuit is from terminal B through the front point of contact 59, wire 62, polarized contact 63 of relay R^6 , wire 64, and thence as before to terminal O . It will be seen that this proceed 90 circuit is closed only when relay R^6 is energized in such direction as to close contact 63, which direction I will term the normal energization of this relay.

The control circuits for each of the signals are similar to those for signal S^5 , and 95 hence they need not be traced in detail herein.

The line relay R^3 for signal S^3 is provided with a circuit which passes from terminal B (see Fig. 4^a) of a suitable source of current, through a pole-changer P^6 operated by signal S^5 , wires 65 and 66, contact 67 of relay R^6 , wires 68 and 69, contact 70 of track relay H^8 , wire 71, contact 72 of track relay H^3 , wire 73, winding of relay R^3 , common 100 wire O' , wire 74 and pole-changer P^5 to terminal O of the same source of current. This circuit, then, is controlled by track relays H^8 and H^3 , and by the line relay R^6 for 105 signal S^6 .

Line relay R^5 for signal S^5 is similarly controlled by line relay R^7 and by track relays H^6 and H^5 , the circuit also including a back contact 75 of a relay X^8 , which relay is referred to hereinafter. Line relay R^7 for signal S^7 is controlled by track relays H^4 and H^7 , and by a pole-changing relay W^9 the control of which is explained hereinafter. 110

When relay W^9 is energized, the circuit for signal relay R^7 is from terminal B of a 115 suitable source of current through the front point of contact 76 of relay W^9 , wire 77, contact 78 of relay H^4 , wire 79, back contact 80 of relay X^6 , wire 81, contact 82 of track relay H^7 , wire 83, winding of relay R^7 , common wire O' , wire 85, from point of contact 86 of relay W^9 , to terminal O of the same source of current. When relay W^9 is de-energized, the circuit for relay R^7 is the same, except that the polarity of the cur- 120 125 130

rent supplied to the latter relay is then reversed due to the fact that the contacts of relay W^9 constitute a pole-changer.

The control of relay W^9 will be explained hereinafter.

Relay R^9 which controls signal S^9 is provided with a circuit which is as follows:

From terminal B of a suitable source of current through pole-changer P^{11} , operated 10 by signal S^{11} , wire 87, contact 88 of track relay H^{11} , wire 89, contact 90 of track relay H^2 , wire 91, winding of relay R^9 , wires 92, 93 and 94, pole-changer P^{11} to terminal O of the same source of current. Relay R^9 is 15 energized in the normal direction when signal S^{11} indicates proceed or caution, and in the reverse direction when signal S^{11} indicates stop.

Relay R^{11} which controls signal S^{11} , is 20 controlled by apparatus in the stretch to the left of the passing siding 51, which apparatus is similar to the apparatus hereinbefore explained for the control of relay R^3 .

The circuit for relay R^5 is provided with 25 a shunt around contact 67 of relay R^5 , which shunt passes from wire 65, through wire 95, contact 96 of an auxiliary relay X^5 and wire 97 to wire 69. Relay X^5 is provided with a pick-up circuit which passes 30 from terminal B of a suitable source of current, through contact 98 operated by signal S^5 , wire 99, back contact 100 of track relay H^5 , wire 101, winding of relay X^5 wire 102, back contact 103 of relay R^5 , to 35 terminal O of the same source of current. This circuit can be closed only when signal S^5 is in the proceed or caution position, track relay H^5 is open and line relay R^5 is open, and consequently, it follows that relay X^5 can be picked up only when a train 40 moving toward the left passes signal S^5 . Relay X^5 is provided with a holding circuit which passes from terminal B of a suitable source of current, through contact 104 of 45 relay X^5 , wire 105, winding of relay X^5 , wire 102, and back contact 103 of relay R^5 to terminal O of the same source of current. It follows, therefore, that when relay X^5 is once closed it will remain closed as 50 long as line relay R^5 remains open.

Relay R^5 is at times removed from control by relay R^7 through the medium of an auxiliary relay X^7 which operates in the same manner as relay X^5 .

55 In so far as the control of the roadside signals is concerned, it remains only to consider the circuits for the pole-changer relay W^9 . This relay is provided with a circuit which passes from terminal B of a suitable source of current, through contact 106 60 operated by signal S^{11} , wires 107, 108 and 109, contact 110 operated by signal S^9 , wire 111, winding of relay W^9 , wires 112, 92, 93 and 94, and pole-changer P^{11} to terminal 65 O of the same source of current. It will be

seen, that, so far as this circuit is concerned, whenever signal S^{11} indicates stop, relay W^9 will be deenergized so that signal S^7 will indicate caution. Relay W^9 is provided with a branch around signal operated 70 contact 106, which branch is controlled by the auxiliary relay X^{11} , and which latter relay is in turn controlled in the same manner as relay X^5 . The branch passes from battery terminal B, through contact 113 of 75 relay X^{11} , and wires 114 and 115, to wire 108. When a train moving toward the left passes signal S^{11} , relay X^{11} becomes closed, so that relay W^9 is removed from control by contact 106, whereupon this relay closes 80 and permits signal S^7 to assume the proceed position.

Signals S^2 , S^4 , S^6 , etc., governing traffic from west to east, are controlled in exactly 85 the same manner as the westbound signals, and consequently a detailed explanation of the circuits for the eastbound signals is unnecessary.

The operation of the system in so far as the trackway signals are concerned is in 90 accordance with standard and usual practice, and hence a detailed explanation is not required. It should be noted, however, that an eastbound train in the stretch of track to the west of siding 51 causes both signals 95 S^9 and S^7 to assume the caution position, but that a westbound train in the same stretch of track permits signal S^7 to return to the proceed position as soon as signal S^9 returns to the caution position. The reason 100 for this selective control of the caution aspect of signal S^7 is well understood.

Each track section and sub-section is provided with means for supplying alternating vehicle governing current to the rails of the 105 section at both ends. Considering sub-section 55a-56, for example, this current is supplied to the battery end through the medium of a transformer T^{10} the secondary of which is included in the track circuit between the battery D and one rail, and the primary of which is at times supplied, as explained hereinbefore, from a transmission line Q which in turn is connected with a suitable source of alternating current not 110 shown in the drawings. At the relay end of this sub-section the vehicle governing current is furnished by a transformer T^{11} , the primary of which is likewise supplied at times from transmission line Q, and the 115 secondary of which is connected across the rails of the section in multiple with track relay H^5 . A resistance 116 is included between the secondary of transformer T^{11} and one track rail to prevent the transformer 120 from forming a low-resistance shunt across the relay H^5 . Each track section is supplied with vehicle governing current in the 125 same manner as sub-section 55a-56.

The supply of vehicle governing current 130

to the track rails is controlled as follows: Considering section 55—56, the supply of current to transformer T^{10} at the west end of sub-section 55a—56, and to transformer T^s at the west end of sub-section 55—55 is controlled by a contact 117 operated by signal S^7 , which contact is closed when this signal is at proceed or caution, but open the signal is at stop. The circuit for transformer T^{10} is from the upper wire of transmission line Q, through wires 118 and 119, contact 117, wires 120 and 121, primary of transformer T^{10} , and wires 122 and 123 to the lower wire of transmission line Q. Transformer T^s is connected in multiple with transformer T^{10} , the branch being from wire 120 through wire 124, primary of transformer T^s , and wires 125 and 126 to the lower wire of transmission line Q. It will be seen, therefore, that vehicle governing current is supplied to the west end of each sub-section of section 55—56 if signal S^7 indicates proceed or caution, but not if this signal indicates stop. In similar manner, the transformer at the east end of each sub-section in section 55—56 is controlled by a contact 117 operated by eastbound signal S^8 . As for section 54—55, the transformers T^s and T^t , which may be termed the eastbound transformers, are controlled by contact 117 of eastbound signal S^s , but the westbound transformers T^u and T^v for this section are controlled by a front contact 127 of pole-changing relay W^u .

Considering now the passing siding section 53—54, the eastbound transformer T^s for this section is controlled by contact 117 on the eastbound signal S^4 , and the westbound transformer T^2 for this section is controlled by contact 127 operated by signal S^{11} . The transformers for section 57—58 are controlled in the same manner as those for section 53—54.

I will now assume that a car or train equipped with the apparatus shown in Fig. 2 or Fig. 3, passes along the track shown in Fig. 4. It will be obvious that whenever such train occupies a section immediately in the rear of signal indicating proceed or caution, a proceed indication will be given aboard the train, but that when the train passes a caution signal the supply of vehicle governing current will be discontinued so that a stop indication will be given on the train, which if desired, may be employed to control the speed of the train so that it will be brought to a stop at the next signal. Assuming then that a westbound train comes to a stop in section 55—56, and that a following westbound train equipped with the apparatus shown in Figs. 2 or 3 passes along the track, it will be seen that the latter train will receive a stop indication immediately after passing signal S^s , because signal S^s will be at stop.

I will now assume that the stretch of track to the west of siding 51 is occupied by a train moving toward the east. Signal S^{11} then indicates stop, while signals S^9 and S^7 both indicate caution. If now a westbound train enters the stretch between sidings 51 and 52, this latter train will receive a proceed indication throughout section 56—57, a proceed indication throughout sections 55—56, but a stop indication immediately after passing signal S^7 because pole-changing relay W^u is open, so that the supply of vehicle governing current to transformers T^u and T^v is discontinued at contact 127. It follows that this westbound train will be brought to a stop or to a low speed in section 54—55, whereupon it may pass signal S^9 and enter the passing siding 51 under control. I will now assume that a westbound train occupies the second sub-section to the west of siding 51, that is, the sub-section corresponding to 56—56a, and that a second westbound train enters the stretch between sidings 51 and 52. Signal S^{11} now indicates stop, signal S^9 indicates caution and signal S^7 indicates proceed because the pole-changing relay W^u is closed. The second westbound train, therefore, receives a proceed indication throughout section 54—55, but it receives a stop indication immediately after passing signal S^9 .

The apparatus shown in Figs. 4, 4a and 4b and thus far referred to would operate in a satisfactory manner except under one condition; namely, when an eastbound train enters the stretch to the west of siding 51 after a westbound train has passed signal S^7 at "proceed" and has entered section 54—55. This eastbound train would cause signal S^{11} to move to the stop position, so that pole-changing relay W^u would open, thus cutting off the supply of vehicle governing current to the train which is moving toward the west in section 54—55. In other words, this latter train would have entered section 54—55 under a proceed indication at signal S^7 and would then receive an unexpected and unnecessary stop indication before reaching signal S^9 . This is particularly disadvantageous in train control systems in which the engineer is penalized for failure to observe signals, and is required to acknowledge stop or caution signals in advance of the change in the indication of the train controlling apparatus in order to avoid some sort of penalty. To avoid this, I have provided means for keeping the pole-changing relay W^u closed after a westbound train passes signal S^7 , provided that it is closed when the train passes this signal. This means comprises a relay L' which serves as a repeater for stick relay X^7 . The circuit for relay L' is from terminal B of a suitable source of current through pole-changer P^u , wires 127, 128 and 129, contact 130 of

relay X^7 , wire 131, winding of relay L' , wire 132, common wire O' , wire 133 and pole-changer P^8 to terminal O of the same source of current. It follows, therefore, that relay L' will be energized when relay X^7 is closed. This latter relay is, of course, closed by a westbound train passing signal S^7 , provided that such signal then indicates proceed or caution. When relay L' is closed it closes a stick circuit for relay W^9 , which circuit is from battery terminal B , through pole-changer P^{11} , wire 87, contact 88 of track relay H^{11} , wire 89, contact 90 of track relay H^2 , wires 91 and 138, contact 137 of relay W^9 , wire 136, contact 135 of relay L' , wires 134 and 109, contact 110, wire 111, winding of relay W^9 and wires 112, 92, 93 and 94, through pole-changer P^{11} to battery terminal O . It will be seen, therefore, that when relays W^9 and L' are closed, the opening of contact 106 operated by signal S^{11} will not cause relay W^9 to open. When a westbound train passes signal S^7 under a proceed indication, therefore, this train will continue to receive a proceed indication until it reaches signal S^9 , even though an eastbound train may in the meantime enter the stretch of track to the west of siding 51. On the other hand, if the westbound train should remain in section 54-55 until the eastbound train traversed the entire section to the left of signal S^{11} and the eastbound train should pass signal S^2 , it is evident that sufficient braking distance no longer exists to permit the two trains to approach each other at speed. Under these conditions the eastbound train will receive a stop indication upon passing signal S^2 at caution, because transformer T^3 is cut off by circuit controller 117 open with signal S^4 at stop, while the westbound train will receive a stop indication wherever it may be in section 54-55 because signal S^9 will go to stop opening the holding circuit of W^9 at circuit controller 110, thus de-energizing W^9 and opening the circuit of transformer T^4 .

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a plurality of successive blocks, a track circuit for each block comprising a source of direct current and a track relay, a transformer for each block whose secondary is included in the connection between one track rail and said source, and means for each block controlled by the track relay for the block next in advance for supplying vehicle governing alternating current to the

primary of the transformer for the block when such track relay is energized but not when the track relay is deenergized.

2. Railway traffic controlling apparatus comprising a plurality of successive blocks, a track circuit for each block comprising a source of direct current and a track relay, and means for each block controlled by the track relay for the block next in advance for supplying vehicle governing alternating current to the track rails of the block in series with said source of direct current when such relay is energized but not when the relay is de-energized.

3. Railway traffic controlling apparatus comprising a plurality of successive blocks, a track circuit for each block comprising a source of track circuit current and a track relay, and means for each block controlled by the relay for the block next in advance for supplying vehicle governing current differing in character from the track circuit current to the rails of the block in series with the source of track circuit current.

4. Railway traffic controlling apparatus comprising a plurality of successive blocks, a track circuit for each block comprising a source of track circuit current and a track relay, and means for each block controlled by the relay for the block next in advance for supplying vehicle governing current differing in character from the track circuit current to the rails of the block in series with the source of track circuit current, a vehicle, and vehicle governing means thereon receiving energy from the track rails and responsive to the vehicle governing current but not to the track circuit current.

5. In combination, a stretch of railway track over which traffic moves in both directions, a track circuit in said stretch comprising a track battery and a track relay connected across the rails at different points, roadside signals for said stretch controlled by said relay, two sources of vehicle governing current connected across said rails adjacent said battery and said relay respectively, and means controlled by a car or train approaching said track circuit for disconnecting from the rails the source of vehicle governing current nearest to such car or train.

6. In combination, a stretch of railway track over which traffic moves in both directions, a track circuit in said stretch comprising a track battery and a track relay connected across the rails at different points, roadside signals for said stretch controlled by said relay, two sources of vehicle governing current connected across said rails in series with said battery and in multiple with said relay respectively, said latter connection including a resistance, and means controlled by a car or train approaching said track circuit for disconnecting from the rails

the source of vehicle governing current nearest to such car or train.

7. In combination, a stretch of railway track over which traffic moves in both directions, a track circuit in said stretch comprising a source of track circuit current and a track relay connected across the rails at different points, two sources of vehicle governing current differing in character 10 from the track circuit current and connected across the rails adjacent the two ends of said track circuit, and means controlled by a car or train approaching said track circuit for disconnecting from the rails the source 15 of vehicle governing current nearest to such car or train.

8. In combination, a stretch of railway track over which traffic moves in both directions, means for dividing said stretch into a 20 plurality of sections and for dividing each section into two sub-sections, signals located adjacent the junctions of adjacent sections for governing traffic through said stretch in both directions, a track circuit for each sub- 25 section comprising a battery at the end nearest the middle of the whole section and a track relay at the other end of the sub-section, a line relay for each signal, means for normally controlling each line relay by the 30 track relays for the section through which the corresponding signal governs traffic and by the line relay for the signal next in advance governing traffic in the same direction, means for at times removing each line relay 35 from control by the line relay by which it is normally controlled, means for each sub-section for normally supplying vehicle governing current to the rails thereof at each end, and means controlled by each line relay when 40 de-energized for disconnecting from the two sub-sections in the rear of the corresponding signal the vehicle governing current which is normally supplied to the ends of such sub-sections nearest to such signal.

45 9. In combination, a stretch of railway track over which traffic moves in both directions, signals governing traffic in one direction through said stretch and other signals governing traffic in the other direction 50 through said stretch, a line relay for each signal, means for normally controlling each line relay by the line relay for the signal next in advance governing traffic in the same direction, means for at times removing each line relay from control by the line relay by which it is normally controlled, track circuits for the stretch for controlling said line relays, means for supplying vehicle governing current to the rails of each track circuit 55 at both ends thereof, and means controlled by each line relay when de-energized for disconnecting from the track circuit immediately in the rear of the corresponding signal the vehicle governing current which is 60

normally supplied to the end of such track 65 circuit nearest to such signal.

10. In combination, a stretch of railway track divided into three successive sections, a signal for the first section, a relay for said signal for causing the signal to indicate 70 proceed or caution according as the relay is closed or open, means controlled by said relay for supplying vehicle governing current to the rails of the first section when the relay is closed but not when the relay is open, 75 means for normally opening said relay when a train enters the third section moving towards the first, and means for preventing the opening of said relay due to a train entering the third section moving towards 80 the first when a train occupies the first section moving towards the third until the train in the third section enters the second section.

11. In combination, a stretch of railway track comprising three successive sections, 85 means for supplying vehicle governing current to the rails of the first section when the other two sections are unoccupied to permit a train to move through the first section towards the third, and for normally preventing 90 such supply when a train enters the third section moving towards the first, and means for preventing the discontinuance of said supply of current due to a train entering the third section moving towards the 95 first while a train occupies the first section moving towards the third.

12. In combination, a section of railway track, a track circuit for the section including a battery connected across the rails of 100 the section, a transformer the secondary of which is included in the connection between said battery and one of the track rails, and means for supplying alternating vehicle governing current to the primary of said transformer.

13. In combination, a stretch of railway track comprising two blocks separated by a passing siding, one block having an insulated section adjacent to said siding, means 110 for supplying vehicle governing current to said section when the second block is unoccupied to permit a train to pass through the section towards the passing siding and for normally preventing the supply of such current when a train enters the second block moving towards the siding, and means controlled by a train in said section moving towards the siding for preventing the discontinuance of the supply of current to such section 115 due to a train entering the second block.

14. In combination, a stretch of railway track comprising two blocks separated by a passing siding, the first block having an insulated section adjacent to said siding, a 120 relay for said section, means controlled by a train in the second block moving toward said siding for preventing said relay from

- closing, means controlled by a train in said section moving towards the siding for preventing said relay from being opened by a train entering the second block moving towards the siding, and means controlled by said relay when closed for supplying vehicle governing current to said section to permit a train to move through the section towards said siding.
- 10 15. In combination, a stretch of railway track comprising two blocks separated by a passing siding, the first block having in insulated section adjacent said siding, a stick relay for said section, a pick-up circuit for said relay opened by a train in the second block moving towards the siding, a holding circuit for said relay closed while a train is in said section moving towards the siding regardless of the entrance of a train into the second block provided said relay is closed when the train enters said section, and means controlled by said relay when closed for supplying vehicle governing current to said section to permit a train to move through the section towards said siding.
- 15 20 25 16. In combination, a stretch of railway track comprising two blocks separated by a passing siding, the first block being provided with an insulated section adjacent said siding, a relay, means for opening said relay when a train enters the second block moving towards the first and for holding it open until such train leaves the second block, a second relay, a pick-up circuit for said second relay controlled by a front contact of the first relay, a holding circuit for said second relay including a front contact of the second relay and a contact closed by a train in said section moving towards the siding, and means controlled by said second relay when closed for supplying vehicle governing current to said section.
- 20 25 30 35 40 45 17. In combination, a section of railway track, a track circuit for the section including a relay connected across the track rails, a transformer the secondary of which is connected across the rails of said section in multiple with said relay, means interposed between said relay and said secondary for preventing the secondary from shunting the track circuit current away from the relay, and means for supplying alternating vehicle governing current to the primary of said transformer.
- 30 35 40 45 50 55 18. In combination, a section of railway track, a track circuit for the section including a relay connected across the track rails, a transformer the secondary of which is connected across the rails of said section in multiple with said relay, a resistance interposed between said relay and said secondary, and means for supplying alternating vehicle governing current to the primary of said transformer.
- 55 60 65 70 75 80 85 19. In combination, a section of railway track, a direct current track circuit for said section including a track relay connected across the track rails, a transformer the secondary of which is connected across the track rails of said section in multiple with said relay, means interposed between said relay and said secondary for preventing the secondary from shunting the track circuit current away from the relay, and means for supplying alternating vehicle governing current to the primary of said transformer.
- 65 70 75 80 85 90 95 100 105 110 115 120 125 20. In combination, a section of railway track, a track circuit for said section including a source of current and a track relay, a transformer the secondary of which is included in the connection between said source of current and the track rails, a second transformer the secondary of which is connected across the rails of said section in multiple with said relay, and means for supplying alternating vehicle governing current to the primaries of said transformers.
- 90 95 100 105 110 115 120 125 21. In combination, a section of railway track, a track circuit for said section including a battery and a track relay, a transformer the secondary of which is included in the connection between said battery and the track rails, a second transformer the secondary of which is connected across the rails of said section in multiple with said relay, means interposed between said secondary and said relay for preventing the secondary from shunting direct current away from the relay, and means for supplying alternating vehicle governing current to the primaries of said transformers.
- 95 100 105 110 115 120 125 22. In combination, a section of railway track, a source of vehicle governing current connected across the rails of said section, and a track circuit for said section including a source of current interposed in the connection between said first source and a track rail and differing in character from such first source.
- 100 105 110 115 120 125 23. In combination, a section of railway track, two sources of vehicle governing current connected with the rails of said section adjacent the ends of the section respectively, and a track circuit for said section including a source of current differing in character from said vehicle governing current and a track relay responsive to said track circuit source.
- 110 115 120 125 24. In combination, a stretch of railway track divided into a plurality of successive sections, a track circuit for each section including a source of current and a track relay connected across the rails, a transformer for each section the secondary of which is interposed between the source of current for the section and a track rail of the section, and means controlled by each

- track relay for supplying alternating vehicle governing current to the primary of the transformer for the adjacent section.
25. In combination, a stretch of railway track divided into a plurality of successive sections, means for supplying vehicle governing current to each end of each section, and a track circuit for each section including a source of current of distinctive character and a track relay for controlling the supply of vehicle governing current to the adjacent end of each of the adjacent sections.
26. In combination, a stretch of railway track divided into a plurality of successive sections, a track circuit for each section, and means controlled by each track circuit for supplying vehicle governing current distinctive in character from the track circuit current to the adjacent end of each adjacent section.
27. In combination, a section of railway track, a track circuit for the section including a relay connected across the track rails, a transformer the secondary of which is connected across the rails of said section in multiple with said relay, and means for supplying alternating vehicle governing current to the primary of said transformer.
28. In combination a section of railway track, a track circuit for said section including a source of direct current and a relay, a transformer the secondary of which is connected across the rails of said section, means for supplying alternating vehicle governing current to the primary of said transformer, and means interposed between said secondary and said track rails for limiting the amount of direct current shunted from said relay by said secondary.
29. In combination, a section of railway track, a track circuit for said section including a source of direct current and a relay, a source of alternating vehicle governing current connected across the rails of said section, and means interposed between said alternating current source and the track rails for limiting the amount of direct current shunted from said relay by said alternating current source.
30. In combination, a stretch of railway track divided into sections, a track circuit for each section including a source of direct current and a track relay, means for each section for connecting a source of alternating vehicle governing current with the rails of the section when the track relay for the section next in advance is energized, a receiving circuit on a vehicle including a coil in inductive relation to a track rail and also including a capacity device whereby the circuit is tuned to resonance at the frequency of said alternating current, and governing means on said vehicle shunted by said capacity device.
31. In combination, a stretch of railway track divided into sections, a track circuit for each section including a source of direct current and a track relay, means for each section for connecting a source of alternating vehicle governing current with the rails of the section when the track relay for the section next in advance is energized, a receiving circuit on a vehicle including a coil in inductive relation to a track rail and also including a capacity device whereby the circuit is tuned to resonance at the frequency of said alternating current, an amplifier on said vehicle having an input circuit shunted by said capacity device, and vehicle governing means controlled by the output circuit of said amplifier.
32. In combination, a stretch of railway track divided into sections, a track circuit for each section including a source of direct current and a track relay, means for each section for connecting a source of alternating vehicle governing current with the rails of the section when the track relay for the section next in advance is energized, a receiving circuit on a vehicle including a coil in inductive relation to a track rail and also including a capacity device whereby the circuit is tuned to resonance at the frequency of said alternating current, an electron tube amplifier on said vehicle, a grid circuit for said amplifier shunted by said capacity device, a plate circuit for said amplifier including a source of direct current, and governing means on the vehicle controlled by the variations in the current in said plate circuit due to alternating potential across said condenser.
